Watter Bottle Stomp Model Rocket. By Genovega. earliest review dated Oct. 7, 2019. found online [Jul. 19, 2020] https://www.amazon.com/Launcher-Outdoor-Science-Experiment-Teenagers/dp/B07XGG3675.*

Primary Examiner — Marissa J Cash

(57) **CLAIM**

The ornamental design for a water rocket, as shown and described.

DESCRIPTION

FIG. 1 is a front elevation view of a water rocket showing my new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front and top perspective view thereof; and,

FIG. 8 is a bottom perspective view thereof.
